UNITED STATES PATENT OFFICE.

HARRY H. KLEIN, OF NEW YORK, N. Y.

WIRE DISTENDER.

1,128,688.

Specification of Letters Patent. Patented Feb. 16, 1915.

Application filed February 17, 1914. Serial No. 819,136.

To all whom it may concern:

Be it known that I, HARRY H. KLEIN, a citizen of the United States, residing in New York city, in the county of New York and State of New York, have invented certain new and useful Improvements in Wire Distenders, of which the following is a specification.

The object of my invention is a light distender, to give form to and approximately fix the boundaries of articles made of light fabrics, such as collars, and sashes, bows and rosettes of ribbon.

In the drawings, all the figures are elevations, except Figure 2. Fig. 1 is an elevation of a distender suitable for use in collars and Fig. 2 a partial plan illustrating the curvature it tends to assume. The remaining figures show distenders that give form to both top and bottom of the fabric article and in which some or all of the component wires are formed into a fret, or frets before being twined or twisted together. Fig. 4 illustrates a distender with one continuous boundary or lateral wire and two fretted transversals or web wires; Fig. 5 one with two lateral wires and one fretted transversal and Fig. 6 one with two laterals and two fretted transversals. Figs. 3 and 7 illustrate distenders made of two fretted wires with their frets alternating and forming continuous laterals and connecting transversals. In Fig. 3 one boundary is generally arcuate and the distender is a succession of segmental figures.

In the forms illustrated in Figs. 1 and 2 the distender comprises a unital lateral wire 1 and a web or transversal wire 2 twined thereabout and looped, or looped and twisted into transversals 3 extending substantially perpendicularly therefrom forming right hand helices R and left hand helices L and separated by bays 4. The transversals have a wide base 5. In the form illustrated in Fig. 1 the transversal wire 2 converges so that the bases 5 are triangular. From the base outwardly the runs of web-wire of each transversal 3 are twisted, separated medially into a loop to form an attachment slot 6, and twisted thence to the terminal eye, 7.

Medially of each bay 4 the lateral wire 1 and web wire 2 are separated into loops to form attachment slots 8. Such a distender attached to a fabric article causes therein

three zones whose flexibility differs in kind and degree, as follows:—a narrow, non-extensible edge zone adjacent to the lateral wire 1; an adjacent, wider zone determined in width and, linearly, in symmetrical relation with the lateral wire 1 by the triangular, bracket-like bases 5, which prevent the web from racking; and a zone universally flexibly distended by the transversals 3, which can be disposed to cause the fabric, when undisturbed, to keep any desired form or convolutions and when disturbed to tend to return thereto; because the fingers are universally flexible, as indicated in dotted lines in Fig. 1. These peculiarities make the device peculiarly adapted to distend bows, rosettes and like ornaments of ribbon. The attachment slots, 6, 8, adapt the distenders to be connected with finely finished fabrics, like satin and silk, without the necessity of marring their surfaces with stitches.

Tags, 9, inserted in the slots 6, 8 and cemented to the fabric securely fix the distender in place without showing, or marring the finish; and without possibility of the distender slipping relatively to the tags, which would occur if the tags 9 were simply laid over the wires, instead of being entered into the slots 6, 8. The formation of the web-wire 2 on the lateral 1 causes the distender to tend to assume a cylindrical form when the ends of the distender are drawn toward one another, as illustrated in Fig. 2.

Figs. 4 to 7 inclusive show distenders for band-like fabric articles, such as belts and closed collars, adapted to give approximate form to both sides thereof, and all made by intertwining fretted transversals with straight laterals or with other fretted transversals.

Fig. 4 shows a distender comprising one continuous lateral 1 and two fretted transversals 2^a and 2^b forming right hand helices R and left hand helices L, both formed with reverse bends, or frets 20 which alternate so as to cause closed bays 40; a reverse-twist boundary formed of the lateral 1 and succeeding lateral runs of the frets of the transversals, and having loops forming medial attachment slots 8; and an opposite single-continuous-wire boundary formed of lateral runs of said frets; and transversal members 3^c formed of the transverse runs of the frets 20 of the transversals 2^a and 2^b, 110

and having loops forming medial attachment slots 6 and reverse twists to opposite sides thereof.

Fig. 5 shows a distender comprising two opposite continuous laterals 1 and 1^a and one transversal 2^a whose transverse runs are the transverse members 3^a, connect the laterals, and with them form closed bays 40; and whose lateral runs form reverse-twist boundaries with medial attachment slots 8 to opposite sides of successive bays.

Fig. 6 shows a distender comprising two continuous laterals 1 and 1^a and two transversals 2^a and 2^b forming right hand helices R and left hand helices L formed with frets 20, combined to form closed bays 40, reverse-twist boundaries with loops forming medial slots 8 and reverse twist transverse members 3^c also with loops forming medial slots 6.

Figs. 3 and 7 illustrate distenders comprising two fretted wires 2^c and 2^a, and 2^c and 2^b, respectively, bent and twisted to form right hand helices R and left hand helices L. In the form shown in Fig. 7 the distender is rectangular, in which the wires 2^c and 2^a have their frets 20 formed with linear lateral runs to each side of them, each wire forming a linear lateral run to one side of one bay, then forming a transversal, and next forming a linear lateral run to the other side of the next bay; their lateral runs form continuous, single-wire boundaries and their transverse runs, reverse-twisted transverse members 3^c with loops forming medial slots 6.

The distenders illustrated in Fig. 3 are formed like those just described save that the wires 2^c and 2^a have their frets 20 formed with alternating arcuate lateral runs, 26 to one side and linear runs 27 to the other.

When finished, the wires 2^c and 2^a form a succession of united distenders segmental in form and adapted for flaps and ornamental figures; or to be combined in circular or 45 polygonal forms. The linear runs 27 of the frets form a discontinuous, substantially straight boundary and the arcuate runs 26 form a succession of segmental boundaries; and the boundaries of each segment are connected by reverse twisted transverse members 3^c with loops forming medial slots 6, formed of the transverse runs of the wires 2^c and 2^a.

Having thus described my invention, I 55 claim:

1. A fabric distender having a lateral wire and a transversal wire twined therewith, and having bends forming transverse members with medial loops forming attachment slots and extending from said lateral wire, and to opposite sides of such bends such wires forming right-hand and left-hand helices respectively. 60

2. In a fabric distender comprising wires bent into frets and twisted together to form bays, runs of wires forming sides thereof and twisted together to form medial slots, and right-hand and left-hand helices to 65 opposite sides of such slots. 70

3. A fabric distender comprising wires bent into frets, the lateral runs of such frets linear to one side, arcuate to the other; said wires united to form segmental figures with the transverse runs and twisted together to form medial slots, and right hand and left hand helices to opposite sides of such slots. 75

HARRY H. KLEIN.
